(57) CLAIM

The ornamental design for a table, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a table in an expanded configuration showing my new design;

FIG. 2 is a top view thereof;

FIG. 3 is a front view thereof;

FIG. 4 is a rear view thereof;

FIG. 5 is a left side view thereof;

FIG. 6 is a right side view thereof;

FIG. 7 is a perspective view of the table in an intermediate configuration between the expanded configuration and a collapsed configuration; and,

FIG. 8 is a perspective view of the table in the collapsed configuration.
